UNITED STATES PATENT OFFICE.

OLIVER D. HUNT, OF COLUMBUS, OHIO.

SWITCH-OPERATING MECHANISM.

SPECIFICATION forming part of Letters Patent No. 747,886, dated December 22, 1903.

Application filed March 21, 1903. Serial No. 148,922. (No model.)

To all whom it may concern:

Be it known that I, OLIVER D. HUNT, a citizen of the United States of America, residing at Columbus, in the county of Franklin and State of Ohio, have invented certain new and useful Improvements in Switch - Operating Mechanism, of which the following is a specification, reference being had therein to the accompanying drawings.

This invention relates to improvements in means for operating switch-points from a moving car; and its object is to provide a simple and efficient construction for the purpose which will require but little space and is all located near the surface of the road-bed where every part is accessible.

A further object is to provide a suitable operating mechanism to be carried by the cars and to provide certain other new and useful features and the particular arrangement and combination of parts, all as hereinafter more fully described, reference being had to the accompanying drawings, in which—

Figure 1 is a plan view of the road-bed, showing the rails, switch-point, and guide-slot, and also showing the operating mechanism with the covers of its casings removed. Fig. 2 is a side elevation of the operating mechanism carried by the car, and Fig. 3 is a front elevation of the same and also showing a cross-section of the slot-plate and one of the casings.

As shown in the drawings, A represents the main-track rails, B the rails of the branch or switch, and C the switch-point. Extending longitudinally of the rails and located, preferably, between the same is the slot-plate D, provided with a longitudinal slot D', the upper angles of which slot are cut away, as shown at D'', to guide the operating-arm E into the slot when said arm is lowered. Each of the cars is provided with one of the operating-arms E, which is pivoted at one end to a bracket F, secured to the truck-frame of the car or other convenient place of attachment, and consists of two parts E' and E'', joined by a hinged joint E''' to allow the arm to yield or double up should it strike an obstruction when lowered, said arm being normally held extended and also in its raised position by a spring G, which is attached at one end to an ear on the lower portion E'' of the arm and at its opposite end to a projecting portion

of the bracket F. Toggle-levers H are pivotally secured at their outer ends to the portion E' of the arm and to the bracket F, respectively, and to the pivot connecting the inner ends of these levers is attached a rod H' for operating the same, a spring H'' being secured on the rod and engaging an ear H''' on the bracket through an elongated opening in which the rod is passed to normally hold the levers off their center. The arm E is provided with rolls I near its lower end, which rolls extend outward from the sides of the arm to engage the top of the slot-plate D and limit the distance which the arm may be thrust into the slot.

Extending longitudinally of the track through suitable bearings J' and bearings formed therefor in the casings K and K' is the longitudinally-movable shaft J, and to the switch-point C is pivotally attached at one end a link L, and at the opposite end said link is pivotally attached to one arm of a bell-crank lever L', which is pivoted to any suitable support and has the outer end of its opposite arm pivotally attached, by means of a link L'', to the end of the shaft J. On the shaft J within the casing K is secured an ear M', which is connected by M'' to one end of the lever or bar M, said lever being pivoted intermediate its ends upon a boss M''' in the bottom of the casing in such a position relative to the guide-slot D' that when turned to one position one end of said lever will be projected across said slot in a position to be engaged by the operating-arm E, and within the casing K' a similar ear N' is secured to the shaft, to which ear is pivotally secured one end of a link N'', the opposite end of said link being attached to one end of a bar N'', which is pivoted intermediate its ends at N''' to a boss on the bottom of the casing and the opposite end of which is connected to the bar N by a second link N''. The bar N is also pivoted intermediate its ends to a boss on the bottom of the casing and so positioned that when moved in one direction it will be projected across the slot in position to be engaged by the arm E, the intermediate bar N''' and link N'' between the bar N and link N'' causing the bar to move in an opposite direction to that of bar M, said bar N being moved across the slot as the bar M is withdrawn, and vice versa. The bars

and links are all placed with their width extending longitudinally, and the bars M and N move directly beneath the slot-plate D. Therefore only shallow cases are required, 5 and as these casings do not set far into the road-bed and are provided with removable top plates K² the parts are readily accessible.

The shaft J is divided near its end adjacent to the switch-point and the two parts united 10 by a yielding connection consisting of a cylinder O, secured to the end of one part, and a piston-head O', secured to the end of the other part within the cylinder, springs O² being interposed at each side of the piston between 15 the piston and the heads of the cylinder to normally hold the piston from moving in the cylinder. The longitudinal movement or throw of the shaft is greater than the throw of the switch-point, so that the point will be 20 thrust hard against the rail, one of the springs O² yielding to allow the shaft to be fully thrown. In this construction one or the other of the bars M N will always be projected across the slot in position to be operated by 25 the operating-arm on the car whether the switch-point has been thrown by the device on a previous car, by the car-wheel of a car going in the opposite direction, or by a pinch-bar, and they cannot throw too far or become 30 inoperative because of not having been thrown far enough, as their movement is limited by the casing, and if both project into the slot the operating-arm will contact the first bar and throw it out of the slot and at 35 the same time throw the other entirely across the slot.

Having fully described the invention, what I claim is—

1. The combination, with a switch-point, 40 of a longitudinally-movable shaft, means for operating the switch-point by the movement of said shaft, pivoted levers adapted to be turned to project their free ends across the path of an arm carried by the car, a link pivotally connecting one of said levers to said shaft, and a bar pivoted intermediate its ends 45 and connected at its ends by links to the other lever and to the shaft respectively.

2. The combination, with a switch-point, 50 of a plate having a guide-slot for an operating-arm carried by the car, a longitudinally-movable shaft, a bell-crank, links connecting the arms of said bell-crank to the shaft and switch-point respectively, levers pivoted intermediate their ends and adapted to be turned to project across the guide-slot, ears 55 on said shaft, a link pivotally connecting one of said ears and one of the levers, a bar pivoted intermediate its ends, a link connecting 60 end of said bar and an ear on the shaft, and a link pivotally connecting the opposite end of said bar and one end of the other lever.

3. The combination, with a switch-point having a limited throw, of a longitudinally- 65 movable shaft divided into two parts and having a greater throw than the switch-point, means for connecting the parts of said shaft

to allow the same to yield longitudinally, a bell-crank connecting the end of said shaft with the switch-point, levers pivoted to turn 70 into and out of the path of an arm carried by the car, and links connecting said levers and the shaft.

4. The combination, with a switch-point, a plate having a guide-slot, and means adapted to project into said slot and connected to said switch-point to operate the same, of a bracket carried by a car, an operating-arm pivoted to said bracket and made in two parts hinged together, a spring attached at one end 80 to the bracket and at its opposite end to said arm beyond its hinge to hold the arm extended and in its raised position, and means for forcing said arm downward to enter the slot. 85

5. The combination, with a switch-point, a plate having a guide-slot, and means adapted to project into said slot and connected to said switch-point to operate the same, of a bracket carried by the car, an operating-arm 90 consisting of two parts one of which is pivoted at one end to the bracket and extends outward therefrom and the other part is hinged to the end of the first part and extends downward, a spring secured at one end 95 to the downwardly-extending part of the arm and at its opposite end to the bracket, toggle-levers pivoted to the outwardly-extending portion of the arm and to the bracket, an operating-rod connected to the joint of said toggle-levers, a spring to normally hold said levers off the center, and rollers on the downwardly-extending portion of the arm to engage the slot-plate. 100

6. The combination, with a switch-point, 105 of a longitudinally-movable shaft divided into two parts, a bell-crank, links connecting the ends of said bell-crank and the shaft and switch-point respectively, a cylinder secured to one end of one of the parts of said shaft, 110 a piston-head on the opposite end of the other part of the shaft, springs engaging the ends of said cylinder and the opposite sides of said piston-head, a plate having a guide-slot for an operating-arm on a car, casings extending 115 outwardly from said plate and beneath the same and provided with bearings for said shaft, levers pivoted intermediate their ends upon bosses in said casings and projecting beneath said plate, ears on said shaft, a link 120 connecting one of said ears with the end of one of said levers, a bar pivoted intermediate its ends to a boss on one of the casings, a link connecting the other ear on the shaft with the end of said bar and a link connecting the 125 other end of said bar with the end of the other lever.

In testimony whereof I affix my signature in presence of two witnesses.
